UNITED STATES PATENT OFFICE.

JAMES E. KENNEDY, OF BACOLOD, PHILIPPINE ISLANDS.

STEAM-GENERATING PLANT.

Application filed October 13, 1924. Serial No. 743,380.

To all whom it may concern:

Be it known that I, JAMES E. KENNEDY, a citizen of the United States, residing at Bacolod, Occidental Negros, Philippine Islands, have invented certain new and useful Improvements in Steam-Generating Plants; and I do hereby declare the following to be a full, clear, and exact description of the invention, such as will enable others skilled in the art to which it appertains to make and use the same.

The invention relates particularly to a novel construction of steam generating plant employing bagasse, or similar moist and bulky fuels, and has for its objects the association of the steam boiler section and a furnace section so constructed and arranged as to affect a maximum efficiency in the combustion of the fuel and in the quantity of steam generated per unit weight of fuel employed, within a comparatively wide range of operative requirements for steam, as, for example, in the operation of sugar making plants, the generating plant being sufficiently flexible to take care of demands put upon it ranging from a relatively heavy overload to a load requiring only a small proportion of the normal capacity of the plant, without sacrificing the important elements of efficiency and economy.

The invention is illustrated in the accompanying drawings, in which:

Fig. 1 is a front elevation, partly in section, on the line 1—1 of Fig. 2, of the plant.

Fig. 2 is a sectional plan view on the line 2—2 of Fig. 3.

Fig. 3 is a vertical longitudinal sectional elevation on the line 3—3 of Fig. 2.

Various types and constructional forms of steam generators employing bagasse and similar moist and bulky fuels have been proposed and installed, heretofore, primarily for the purpose of utilizing the bagasse and like materials, which have proven troublesome waste products in the industries, for the fuel values thereof, but practically all of the former installations have proven more or less unsatisfactory, because of the difficulty in effecting complete combustion of the moist fuel and a concomitant difficulty of delivering the products of combustion to the boiler unit, so distributed

as to effect maximum efficiency in the generation of steam. A further objection to the former types of bagasse burning furnaces employed as heating units for boiler plants is the practical inability to accurately regulate the steam generated to the needs of the mechanism in which the steam is employed, as, for example, in sugar boiling plants and the like, because of the fact that the furnaces of the steam generating plants are designed primarily to operate on a given load and are wholly lacking in flexibility to accommodate overloads or underloads. The instant invention involves a coordination of the boiler and furnace units, that will correct all of these objections and difficulties and provide a furnace unit, having sufficient flexibility of operation to enable the steam generating plant as a whole to be worked under conditions of maximum efficiency and economy not only when the plant is worked at normal capacity, but also under sudden demands requiring an overproduction of steam, and, conversely, when the plant is operated at a subnormal load. These desirable objects are obtained by the particular construction of the various units constituting the furnace section of the plant and the coordination of said furnace section with the boiler section.

Referring to the drawings, A represents the boiler section as a whole and B the furnace section. The boiler section preferably comprises the usual installation of a water tube boiler, the particular boiler illustrated in the fragmentary view in the drawings being of the well known Sterling type, which is housed in the usual masonry structure reinforced by beams and girders, as will be understood by those skilled in the art. The boiler housing is graphically represented in the drawings as involving a front wall 1, a rear wall 2 and side walls 3 and 4. The boiler unit, represented by the numeral 6, includes the usual mud drum and the inclined tubes connecting the latter with the top structure of the boiler and interposed in the course of the products of combustion from the furnace section. The usual transverse fire wall 5 is disposed in the boiler section to protect the mud drum from direct contact with the hot products of combustion. It will be understood that

the boiler section is provided with the usual structural and operative elements common to boilers of this type.

The furnace section B which is disposed in advance of the boiler section A is of considerable greater width than the boiler section and comprises a front wall 10, side walls 11 and 12 parallel with the longitudinal axis of the wall structure and converging side walls 11' and 12', which connect the parallel side walls 11 and 12 with the side walls 3 and 4, respectively of the boiler section. Extending longitudinally of the furnace section and throughout the length of the latter is a division wall 13, which divides the furnace section into halves and each half furnace section is subdivided by a generally longitudinal vertical wall, the rear portion of which is deflected toward the central wall, one of these subdividing walls being represented by 14 and 14' and the other by 15 and 15'. The side walls 11 and 12 and the initial portions of the division walls 13, 14 and 15 are substantially parallel and define four relatively deep grate chambers and the initial portions of four corresponding combustion chambers. Spanning the spaces between the side walls of the furnace section and the subdivision walls 14, 14' and 15, 15' and between said subdivision walls and the central wall 13, are arched crowns, three of which, 17, 18 and 19, are shown, and spanning the spaces between the side walls of the boiler section A and the extension of the central wall 13 beyond the ends of the subdivision walls 14' and 15' are arched crowns 20 and 21, the inner ends of the respective crowns being inclined downwardly, as at 20' and 21', to serve as reverberatory deflectors for the products of combustion and to direct said products onto the lower portions of the water tubes of the boiler.

Disposed transversely of the furnace section and extending longitudinally thereof from the grate sections to the inner limits of the arches 20 and 21 is a generally arch-shaped fire bridge 30 at the highest point 30' of which the division walls 14' and 15' terminate. By this construction, there are provided four separate grate and combustion chambers which provide relatively large initial chambers to receive the bagasse and in which preliminary drying and complete combustion of the fuel may be effected, the products of combustion passing upward from the grate chambers being deflected by the wall sections 11', 14', 15' and 12' toward the central wall 13, the products from the two grates in each half of the furnace being delivered and commingled in the discharge sections of the combustion chambers lying on either side of the central wall 13, and the prod-

ucts of combustion from the grates in both halves of the furnace being commingled beyond the inner end of the central wall 13 and directed downwardly by the inclined crowns 20' and 21' onto the lower sections of the boiler tubes, and meeting the fire wall 5 are thence directed upwardly over the various tubes and ultimately to the stack, as will be understood.

Each of the initial sections of the four furnace chamber is provided with a flat grate 31 located at the foot of the fire bridge 30 and associated with each flat grate section is a relatively steep stepladder grate 32 extending from the forward portion of the flat grate to the front wall 10 of the furnace chamber. Located above each of the stepladder grates 32 is a fuel feed opening 25, which extends through the top of the furnace section and communicates with any suitable type of feeding mechanism 26 for delivering the bagasse or similar fuel to the furnace, the feed opening and chute being defined by the front wall of the furnace and a curtain arch 22 extending downwardly from the top of the furnace to a point above the stepladder grate. The front wall of each furnace section is provided with the usual stoke opening 27 and ash pit opening 28 provided with suitable closures. Preferably the stepladder grates are blanked off for the greater part of their area in order to prevent setting up back drafts and to insure that the supply of the combustion supporting air passes upward through the fuel on the flat grates 31.

The function of the stepladder grates is primarily to provide for a preliminary drying of the bagasse, or similar fuel, before the latter is delivered onto the flat grates where combustion is effected. If conditions are met when this preliminary drying is found to be unnecessary, obviously, the stepladder grates may be dispensed with and the bagasse delivered directly to the flat grates.

In the normal operation of the apparatus as described, the bagasse, or similar fuel, is fed in through the chutes 25 in properly regulated quantities directly onto the inclined stepladder grates 32, down which the fuel passes slowly and is ultimately discharged onto the flat grates 31. During the passage of the bagasse over the stepladder grates, the products of combustion of the bagasse being burned on the flat grates pass upwardly over the bagasse on the stepladder grates and take up the moisture in the bagasse, so that the latter is delivered to the flat grates in proper condition to effect combustion, which latter condition may be assured by a properly regulated supply of air by any of the well known means usually employed for this purpose and

which are so well understood as to require no specific illustration. The combustion initiated in the fuel on the flat grates is completed as the gaseous products rise and pass over the bridge wall, an intimate admixture of the air being assured by the constriction of the combustion spaces defined by the arched fire bridge 30 and the relatively converging walls of the combustion chambers, the combustion products from the two sets of chambers constituting each half of the furnace section commingling in the common discharge chamber of each half section defined by the central wall 13, the side walls 3 and 4 of the boiler section and the downwardly inclined crowns 20' and 21' and the products from all of the combustion chambers being commingled in the initial portion of the boiler section beyond the central wall 13 and the bridge wall 30 and the crowns 20' and 21'.

From the foregoing, it will be apparent that, when the steam generating system is operating under normal capacity, all four of the grate sections will be supplied with properly regulated amounts of bagasse, and, when extraordinary demands are put upon the generator, in case of overload, a relatively larger proportion of fuel and air will be fed to the several grate and combustion chambers. When, however, the output of the boiler is to be reduced to meet a decreased demand for steam, the desired result may be obtained by blanking off a portion of the flat grates 31, by placing rows of bricks thereon, or, in the alternative, the feed of the fuel to one or more of the grates may be suspended, and, if desired, the particular grate or grates not receiving fuel may be blanked off by covering the surface thereof with bricks, or the like. In any event, however, the grate and combustion chambers which are maintained in operation will effect a thorough and complete combustion of the fuel fed thereto and direct the products of combustion from both halves of the furnace section into the boiler section to produce a thorough commingling of the products of combustion and the direction of the same against the lower ends of the boiler tubes, as hereinbefore explained. It has been found that the furnace, as described, maintains its efficiency and economy of operation, practically unimpaired, whether two, three or four of the grate sections are operated, provided the operated grates are located on opposite sides of the central wall 13. It will be seen, therefore, that the installation, as described, provides ample grate area for any conditions of operation, insures complete combustion of the fuel under all conditions of operation, facilitates the economical production of the amount of steam desired without impairing the efficiency of the steam generation and en-

ables the plant to be operated to meet any required conditions of steam generation from a relatively high overload to a load comparatively far below normal without material loss in either efficiency or economy. 70

What I claim is:

1. A steam generating plant employing bagasse or similar fuel, comprising a boiler section having a boiler therein, and a furnace section of greater width than the boiler section and connected therewith by converging side walls, said furnace section including two pairs of grate and combustion chambers divided by a longitudinal wall and having arched crowns, an arched fire bridge 75 extending substantially from the grate chambers to the discharge ends of the combustion chambers, the dividing wall between the pairs of chambers extending longitudinally throughout the length of the furnace section and the dividing walls between the chambers of each pair terminating approximately at the highest point of the bridge wall. 80

2. A steam generating plant employing bagasse or similar fuel, comprising a boiler section having a boiler therein, and a furnace section of greater width than the boiler section and connected therewith by converging side walls, said furnace section including two pairs of grate and combustion chambers divided by a longitudinal wall and having arched crowns, an arched fire bridge 90 extending substantially from the grate chambers to the discharge ends of the combustion chambers, the dividing wall between the pairs of chambers extending longitudinally throughout the length of the furnace section and the dividing walls between the chambers of each pair terminating approximately at the highest point of the bridge wall, the portions of the latter dividing walls which overlie the fire bridge being deflected laterally toward the central wall. 95

3. A steam generating plant employing bagasse or similar fuel, comprising a boiler section having a boiler therein, and a furnace section of greater width than the boiler section and connected therewith by converging side walls, said furnace section including four grate chambers and four combustion chambers, a central wall extending throughout the length of the furnace section dividing the grate chambers and combustion chambers into pairs, division walls between the grate and combustion chambers of each pair terminating short of the inner end of the central wall and each having an end portion deflected toward said central wall, four arched crowns spanning the five chamber defining side and division walls, two arched crowns spanning the side walls and the central wall, and an arched fire bridge extending transversely of the furnace section and longitudinally of 100

110

115

120

the same substantially from the grate chambers to the inner end of the furnace section.

4. A steam generating plant employing bagasse or similar fuel, comprising a boiler section having a boiler therein, and a furnace section of greater width than the boiler section and connected therewith by converging side walls, said furnace section including four grate chambers and 10 four combustion chambers, a central wall extending throughout the length of the furnace section driving the grate chambers and combustion chambers into pairs, division walls between the grate and combustion chambers of each pair terminating short of the inner end of the cen-

tral wall and each having an end portion deflected toward said central wall, four arched crowns spanning the five chamber defining side and division walls, two arched crowns spanning the side walls and the central wall, an arched fire bridge extending transversely of the furnace section and longitudinally of the same substantially from the grate chambers to the inner end of the 25 furnace section, flat grates near the bottoms of the grate chambers, and steeply inclined stepladder grates disposed between the front wall of the furnace section and the flat grates. 30

In testimony whereof I affix my signature.
JAMES E. KENNEDY.
